(57) CLAIM

The ornamental design for a holder for elongated articles, such as pens and pencils, for attachment to a wall, such as a cubicle wall, as shown and described.

DESCRIPTION

A portion of the disclosure of this patent document contains material to which a claim for copyright is made. The copyright owner has no objection to the facsimile reproduction of the patent document or the patent disclosure, as it appears in the Patent and Trademark Office patent file or records, but reserves all other copyrights whatsoever.

FIG. 1 is a perspective view of a holder for elongated articles, such as pens and pencils, for attachment to a wall, such as a cubicle wall, embodying our new design; FIG. 2 is a front elevational view thereof;

FIG. 3 is a rear elevational view thereof;

FIG. 4 is a side elevational view thereof; and,

FIG. 5 is a top plan view thereof, the structure depicted by means of broken lines being shown for illustrative purposes only and forming no part of the claimed design.
